UNITED STATES PATENT OFFICE.

ISAAC ALBERT BAUM, OF MEMPHIS, TENNESSEE.

PLASTER TERMINAL.

Application filed January 14, 1926. Serial No. 81,325.

My present invention relates generally to door and window openings, and more particularly to plaster terminals constructed and for utilization in connection therewith in such manner as to cooperate with the frames around door and window openings and to supplant, and do away with the necessity of, the usual inside blind stops or door frame finishing strips, and the primary object of my invention in thus doing away with the necessity of inside blind stops as well as frame finishing strips, is the elimination of divisions of, or cracks between, the adjacent materials whereby to render such frames more nearly vermin-proof than has heretofore been possible, as well as to provide against air leaks and the like.

In the accompanying drawing which illustrates my present invention and forms a part of this specification,

Figure 1 is a sectional perspective view through one side of a window frame illustrating the practical application of my invention in connection therewith,

Figure 2 is a sectional perspective view through one lower side portion of a door and its frame illustrating another practical application of my invention, and

Figure 3 is a detail perspective view of a portion of the plaster terminal proposed by my invention.

Referring now to these figures, and particularly to Figure 3, my invention proposes a plaster terminal formed of metal, with a flat, or substantially flat, body portion 10 of sufficient width to span one side of a window frame box or to solidly attach to wall studding adjacent to a door frame. This body may, if so desired, be crimped, corrugated or otherwise impressed to lend the same additional strength, and may be notched, apertured, or struck up to insure the retention of plaster placed thereagainst.

The body 10 of the plaster terminal as proposed by my invention is furthermore provided along one edge with an approximately right angular flange 11, and the latter has in turn along its free edge an inwardly bent lip 12 provided with a reverting free edge 13, the lip 12 and flange 11, together with a portion of the body 10 cooperating to form substantially a channel into which wall

plaster is, in accordance with my invention, extended around a window or door frame whereby the plaster is protected, the reverting free edge 13 of the lip being embedded in the wall plaster so extended in order to permanently insure proper positioning of the lip 12 as well as to prevent the latter from becoming misshapen.

In Figure 1 I have shown one manner in which my invention may be utilized in lieu of one inner side of a window frame box to do away with the necessity of what is commonly known as the inner blind stop, the body 10 of the plaster terminal closing the inner side of the window frame box 14 so that the wall plaster 15 may be extended continuously across the body 10 and into the channel formed for its reception by the body 10, flange 11 and lip 12.

In Figure 2 I have shown an arrangement of plaster terminal adjacent to a door 16 and its jamb 17, the body 10 of the plaster terminal being in this instance simply used to securely fasten the plaster terminal to wall studding 18, utilizing the studding 18 and door jamb 17 as a guide so that the wall plaster 19 may be extended continuously to the jamb 17 where the flange 11 and lip 12 project, it being understood that the studding 18 and door jamb 17 are already in place when the plaster terminal is applied, so that the latter needs no further alignment.

It is obvious from this that the usual finishing strips are avoided, and not only is a combustible part of the ordinary window and door casing eliminated, but cracks and crevices are done away with, the leakage of air around window frames especially is avoided, and such structures rendered much more nearly vermin-proof than is possible with the present structures and methods.

I claim:

A finishing strip for the plaster side of a wall opening comprising a channel strip of metal with one side flange of a width for suitable anchoring the strip and substituting for the blind stop in a casing about a wall opening, and a bridge portion corresponding in width to the thickness of plaster upon the wall.

ISAAC ALBERT BAUM,
